UNITED STATES PATENT OFFICE.

GEORGE W. KINTZ, OF SANTA MONICA, CALIFORNIA.

CURTAIN-FIXTURE.

No. 807,621.

Specification of Letters Patent.

Patented Dec. 19, 1905.

Application filed December 2, 1903. Serial No. 183,534.

To all whom it may concern:

Be it known that I, GEORGE W. KINTZ, a citizen of the United States, residing at Santa Monica, in the county of Los Angeles and State 5 of California, have invented new and useful Improvements in Curtain-Fixtures, of which the following is a specification.

The object of my invention is to provide a fixture that is detachably connected to the 10 window-sash which will carry on it both the window shade and curtain, so that, if desired, the curtain and shade and fixture may be removed together from the window and the same left clear for cleaning.

15 My invention also has for another object detachably securing to the frame and to the window-sash wire screening, one end of which is connected to a revoluble roller upon which it is automatically wound when the window-sash 20 is in its closed position and unwound to cover the opening left by the lowering of the upper sash.

25 My invention is described herein and illustrated in the accompanying drawing, which is 25 a perspective view of a fragment of the upper portion of a window and sash equipped with my improved fixtures.

In the drawing, A is the window-frame of 30 ordinary construction, in which is slidably mounted the upper sash B, to the side rails of which, near the upper end thereof, are removably secured brackets C, which carry on their outer ends shade D and curtains, (not shown,) if desired. The base C' of these brackets is 35 provided with attaching-pins E, which fit into sockets F in the side rail of the sash. The upper part of the base is formed into a hook C'' for the reception of the hook G' of the wire G, which wire is affixed to strip H, to which 40 the lower end of the screen I is fastened. The pins E project downwardly at an angle to the rear face of the base of the bracket, and the sockets F have a corresponding slant upwardly in the side rail of the sash for the reception of the pins. By this construction the 45 downward pull on the outer end of the bracket causes the pins to lock in the sockets and the bracket to be firmly fastened to the sash, and when the pressure on the bracket is removed 50 the pins can be easily drawn out of the sockets.

The upper end of this screen is secured to a spring-actuated roller T, upon which the screen is wound as the window-sash moves upward, said roller being actuated by the internal 55 spring U, secured thereto in the usual man-

ner. Strip H is provided with a number of pins L, which fit into sockets M in the upper rail of the sash and attach the strip to the sash. Near the outer end of the bracket a bar K projects laterally therefrom, an S-shaped hook R 60 extends in an outwardly direction from the bar K to receive a certain hole, and the outer end of the hook is provided with pintles S for the reception of curtain-rods. The hook is provided with a slot N for the reception of the 65 stationary pintle-bolt (not shown) of the curtain D. The companion bracket is provided with a hole O to receive the revoluble pintle-bolt P.

70 It will be observed that the attaching-pins of the brackets and of the strip to which the lower end of the screen is attached are easily inserted in their respective sockets and will hold the brackets and strips securely attached to the window-sash, and that when it is desired to clean the window both can be easily removed from the sash, and that the strip to which the lower end of the screen is attached can be readily detached from the brackets and the screen permitted to roll up out of the 75 way, while the brackets, with the shades and curtains attached thereto, can be removed from the window, when the same can be cleaned, and that when cleaned they can be readily replaced. It will also be observed that when 80 the upper sash is lowered it carries with it the shade and curtain, so that neither of them are affected by the draft of air which comes in through the open window, and that at the same time the window-screen is brought down 85 to cover the opening made by the lowering of the sash, thereby preventing insects from coming into the room. It will be observed that the shank of the bracket extends outwardly from the sash-rail until it passes beyond the outer face of the window-frame and then turns outwardly and forwardly a sufficient distance to carry the ends of the window-shade to cover a portion of the frame, so as to prevent the entrance of light into the room 90 at the edges of the shade.

Having described my invention, what I claim as new, and desire to secure by Letters Patent, is—

1. The combination with a window-frame, 105 a sash, a spring-roller supported by the frame, a netting wound on the roller, and a strip secured to the free edge of the netting, of curtain-fixtures secured to the sash, and having hooks thereon, and means extending from 110

said hooks to the strip for connecting the netting to the sash, the fixtures constructed and adapted to support a curtain.

2. The combination of a window - bracket having a plurality of attaching-pins secured to the base thereof, and a hook on the upper part of said base; a window-sash having a plurality of sockets near the top thereof adapted to receive the attaching-pins of the bracket, said window-sash also having a plurality of sockets in the top rail thereof; a window-casing; a spring-operated screen mounted in said window-casing having an attaching-strip at

the bottom thereof provided with a plurality of attaching-pins adapted to be inserted in the 15 sockets of the top rail of the window-sash; a hook secured to said attaching-strip and said bracket.

In witness that I claim the foregoing I have hereunto subscribed my name this 27th day 20 of November, 1903.

G. W. KINTZ.
